UNITED STATES PATENT OFFICE.

GEORGE LEE, OF BELLEVILLE, WIS., ASSIGNOR OF ONE-THIRD HIS RIGHT TO D. S. SMITH AND ONE-THIRD TO JOSEPH AND THOMAS BRAMWELL WITHERS, OF SAME PLACE.

IMPROVEMENT IN SAWING-MACHINES.

Specification forming part of Letters Patent No. 178,168, dated May 30, 1876; application filed April 22, 1876.

To all whom it may concern:

Be it known that I, GEORGE LEE, of Belleville, in the county of Dane and State of Wisconsin, have invented a new and valuable Improvement in Sawing-Machines; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a side elevation of my drag-saw attachment.

This invention has relation to drag or cross-cut saws which are operated by wind-wheels; and the nature of my invention consists in a novel arrangement of levers in combination with a crosscut-saw and a vertically-movable rod, whereby endwise motion is communicated to the saw by the rotation of the wind-wheel, as will be hereinafter explained.

In the annexed drawings, A designates the pillar of a wind-wheel, which is, preferably, constructed of triangular form, with a vertical central standard, *a*, in the center of it. At the upper end of the standard *a* is a short shaft, *b*, which is cranked on both ends. One crank is suitably connected to the wind-wheel shaft, and the other crank is pivoted to the upper end of a rod, C, which extends down one side of the post or standard *a*, and is suit-

ably guided and allowed free vertical motion. D designates a lever, which is pivoted at one end to the pillar A, and at the other end is connected by a link, *c*, to an angular lever, E, which is also pivoted to the pillar A. The lever D is pivoted at or near the middle of its length to rod C, and the latter is free to vibrate and accommodate itself to the movements of the said lever D, so that there will be no binding of the parts during the operation of the mill. The right-angular lever E is strengthened by means of a brace, *f*, and the lower longest arm of this lever is pivoted to one end of a pitman-rod, G, the opposite end of which rod has pivoted to it a saw, S, that is free to rise and descend. When the wind-wheel is rotating, the saw will receive a rectilinear motion, and will descend into the log by its own gravity as the work progresses.

What I claim as new, and desire to secure by Letters Patent, is—

In combination with a wind-wheel pillar, A, the rod C, levers D and E, link *c*, pitman-rod G, and crosscut-saw S, substantially as described.

In testimony that I claim the above I have hereunto subscribed my name in the presence of two witnesses.

GEORGE LEE.
